UNITED STATES PATENT OFFICE.

EDGAR N. DOLLIN, OF SYRACUSE, NEW YORK.

DIECASTING MACHINE.

Application filed June 29, 1921. Serial No. 461,254.

To all whom it may concern:

Be it known that I, EDGAR N. DOLLIN, of Syracuse, in the county of Onondaga, in the State of New York, have invented new and useful Improvements in a Diecasting Machine, of which the following, taken in connection with the accompanying drawings, is a full, clear, and exact description.

This invention relates to what is commonly known as a diecasting machine in which the molding dies are mounted in and upon a suitable carriage for reciprocation into and out of registration with the discharge nozzle of a conduit containing molten metal which is forced into the dies by air pressure applied to one end of the conduit.

The main object is to provide a more facile, economical and efficient apparatus for producing diecastings whereby to greatly increase the output with a minimum expenditure of time and labor.

One of the specific objects is to combine the container and delivery conduit for the molten metal as a unitary article of manufacture and to install the same in the fire box in such manner that both will be exposed to the more intense heat of the burner or burners for the purpose of not only reducing the material to be molded to a molten state in the container but also maintaining and increasing the fluidity of the molten metal which may be placed in the conduit for delivery to the dies under pressure.

Another specific object is to provide means whereby one of the die sections may be automatically closed and open upon and from the other die as the carriage is moved to and from its closed position.

A further object is to construct the carriage operating means in such manner as to automatically lock the carriage in its extreme closed and open positions.

A still further object is to provide resilient means for counter-balancing and assisting in the operation of the carriage particularly in shifting the same from its open to its closed position and to automatically render the counter-balancing means effective by the storage of power therein during the opening movement of the carriage.

Other objects and uses relating to specific parts of the machine will be brought out in the following description:

In the drawings:

Fig. 1 is a top plan of a diecasting machine embodying the various features of my invention, the die-carriage being shown in its closed position.

Fig. 2 is a side elevation partly in section of the same machine as shown in Fig. 1, the dotted lines indicating the open position of the carriage and its operating means.

Fig. 3 is an enlarged transverse vertical sectional view taken on line 3—3, Fig. 2.

Fig. 4 is an end view of the same machine omitting the die carriage.

Fig. 5 is a detail vertical sectional view taken on line 5—5, Fig. 4.

As illustrated, this machine comprises a supporting base or frame —1—, a fire box or heating chamber —2—, a combined melting pot and conduit —3— for the molten metal mainly within the heating chamber —2—, a die supporting carriage —4— and operating means therefor for moving the dies into and out of registration with one end of the conduit, and means for supplying and controlling compressed air to the other end of the conduit for forcing the molten metal into the dies.

Heater.

The fire box or heating chamber —2— is supported upon the upper face of the base or main frame —1— and is provided with one or more openings —5— for the reception of gas, oil or other suitable burners (not shown) as the means for supplying heat to the fire box or heating chamber —2— for reducing and maintaining the metal in the combined melting pot and conduit —3— to and in a molten state. This fire box is preferably circular in top plan and is capped by a suitable ring —6— having a down-turned marginal flange —7— surrounding the adjacent upper end of the fire box for holding the ring against lateral displacement and permitting it to be removed by vertical displacement.

Melting chambers.

The combined melting pot and delivery conduit —3— is supported upon the cap ring —6— within the opening therein and mainly within the fire box —2— so that practically the entire area of the melting

pot as —8— and major portion of the delivery conduit as —9— are directly exposed to heat within the chamber —2—, said melting pot being substantially semi-spherical and separated from the conduit —9— by semi-circular partition —10— forming the upper and side walls of the conduit —9— which is therefor external to the melting pot so as to extend circumferentially around the lower side thereof to expose the major portion of its bottom and side walls to the heat within the chamber —2—, said conduit being relatively narrow transversely as compared with the width of the melting pot or chamber —8—.

The melting pot is preferably open at the top to permit the insertion of the material to be melted therein while the conduit is cut off from communication therewith by 20 the interposed partition —10— and has its opposite ends extended above the level of the melting pot for connection with the dies and with a suitable conduit leading from the source of air pressure supply, which 25 latter is employed to force the molten metal in said conduit through the discharge nozzle when the dies are registered therewith.

The combined melting pot —8— and conduit —9— constitute a closure for the opening in the cap-ring —6—, the air inlet end of said conduit being provided with an annular flange —11— having a vent opening —12— for the escape of gases from the heating chamber —2— and is provided with a seat for the reception of a coupling member —13— by which the air supply pipe as —14— may be firmly clamped by bolts —15— to the adjacent end of said conduit.

40 Any suitable construction of valve as
—16— may be interposed in the connection
between the source of air supply and pipe
—14— to control the pressure in the con-
duit —9— so that when open, the molten
45 metal in said conduit will be forced by
the pressure of the air therefrom into the
dies when the latter are registered with the
delivery end of the conduit.

The molten metal is taken from the melting pot —8— by means of a ladle or equivalent device and poured into the conduit —9— through its delivery end as —17— which constitutes a nozzle having a rounded upper face adapted to fit snugly into and against a corresponding socket in the under side of the fixed section of the dies when the die-carriage is closed to allow the molten metal to be delivered directly into said dies by the pressure of the air in the air inlet end of the conduit, the object in extending the nozzle upwardly beyond the level of the melting pot being to permit the relatively stationary die-section to be brought into close contact therewith.

65 The passageway through the conduit
—9— is tapered from the air inlet end to

the discharge nozzle —17— in order that the inlet opening in the mold may be relatively small and the force of expulsion of the molten metal from the conduit relatively high.

Die-carriage.

The die-carriage —4— preferably comprises a vertically oscillating platform —18— and a series of, in this instance four, posts —19— secured at one end to one end of the platform in spaced relation preferably at the corners of a rectangle and extending in the same direction from said platform in parallel relation so as to become a unitary part of the carriage to move therewith. 75 80

This platform is pivoted intermediate its ends at —20— to upstanding brackets —21— on the main supporting frame —1— to swing about a horizontal axis some distance to one side of the fire-box —2— and melting-pot —8— and in a plane just below the upper face of the cap-ring —6— to allow the end of the plate —18— carrying the posts —19— to assume a substantially horizontal position when the carriage is closed and also to enable the plate to assume a substantially vertical position when open.

Carriage operating means.

The end of the carriage plate —18— opposite to that to which the posts.—19— are secured is pivotally connected at —22— to one end of a pair of similar tubular members —23— containing coil springs —24— and one end of a pair of rods —25—, the other ends of said rods being connected to a yoke —26— which in turn is journaled on or pivoted to a pair of brackets —27— on the main supporting frame —1— to establish a longitudinally resilient toggle connection between the oscillating carriage and frame of the machine and thereby to assist the opening and closing movements of said carriage.

That is, the flexing joint —22— between the platform —18— and tubular members —23— assumes a position some distance above a direct line between the axes of the pivots —20— and —26— when the carriage is closed, and is moved to a position some distance below said direct line when the carriage is open, said tubular members —23— being slidable lengthwise of and upon the rods —25— with and against the action of the coil springs —24— which are interposed between the outer end walls —28— of the tubular members —23— and suitable shoulders —29— on the inner ends of the rods —25— as shown in Fig. 5. These springs are placed under compression in both the closed and open positions of the carriage to partially counter-balance the weight thereof and to assist in opening the

carriage from its closed position and also to assist in closing the carriage from its extreme open position, thus greatly reducing the power required for the positive operation of the carriage from each extreme position to the other.

The outer end of the platform —18— is provided with a stud —30— projecting downwardly from the longitudinal center thereof near the pivot —22— for receiving and supporting a cross-arm —31— to which are attached one end of a pair of longitudinally extending guide-rods —32— in transversely spaced relation and having their other ends secured to suitable bearings —33— on the pivotal shaft —20— to swing vertically with the platform —18— as a substantially integral part thereof.

A bell crank lever —34— is pivoted at —35— to the bracket —21— to swing about a horizontal axis parallel with that of the platform pivot —20— and is provided at one side with a pair of arms —36— carrying at the upper ends pivoted heads —36— which are slidable lengthwise of and upon the rods —32—, the other side of said bell crank being provided with a single arm —37— which is pivotally connected at —38— to one end of a piston rod —39—, the other end of said piston rod being movable in a gland —40— in one end of a cylinder —41— and is provided with a piston —42— movable lengthwise of and within said cylinder.

The cylinder —41— extends lengthwise of the machine and is provided with opposite trunnions —43— journaled in bearings —44— in opposite sides of a supplemental support —45— on the main frame —1— to permit said cylinder to swing vertically about a horizontal axis and thereby to conform to the arc of movement of the pivotal connection between the piston rod and lower arm —37— of the bell crank lever —34—.

The piston —42— may be operated in reverse directions by any suitable fluid, such as air under pressure admitted to and exhausted from the cylinder at either end of the piston according to the direction and movement required. The passage of the motive fluid to and from the cylinder may be controlled by any suitable controller, such for example, as that shown in my pending applications Serial #312,248 filed July 23, 1919 or #374,222 filed April 15, 1920, said controller being shown as comprising a valve case —46— having a main supply pipe —47— leading thereto and branch pipes —48— and —49— leading therefrom to opposite ends of the cylinder, said branch pipes being flexible to permit the oscillation of the cylinder as the carriage is open and closed.

The valve is also provided with an exhaust pipe —50— and an operating lever

—51— by which the air to and from the cylinder is controlled at will to cause the operation of the piston —42— in reverse directions.

Die-operating-means.

The dies or mold may be of any suitable construction depending upon the article to be cast and preferably comprises opposed sections —52— and —53—, one of which is fixed by any suitable fastening means to the platform —18— to register its inlet with the nozzle —17— while the other die as —53— is moved automatically toward and from the fixed die —52— as the carriage is closed and open, and for this purpose is connected by bars —54— to a cross-head —55— which in turn is slidable lengthwise of and upon the posts —19—. This cross-head —55— is connected by a pair of toggles —56— to a cross-plate —57— which is adjustably mounted upon the posts —19— to regulate the movement of the cross-head —55— and its movable die —53— and is held in its adjusted position by lock nuts —58—, each toggle comprising a link —59— and a crank arm —60—, the latter being keyed or otherwise secured to parallel shafts —61— on the cross-plate —57—.

That is, each crank shaft is provided with a pair of crank arms —60— on opposite ends thereof and each crank arm is provided with a plurality of apertures —62— at different distances from the axis of its shaft —61— for receiving pivotal bolts —63— and permitting the length of the toggles to be extended or shortened for varying the amount of movement of the movable die through the medium of its cross-head —55—. Each crank shaft is also provided with a pair of gears —62—, those on one shaft meshing with those on the other shaft to transmit motion one from the other.

An additional crank shaft —63— is journaled in suitable brackets on the cross-plate —57— parallel with the crank shafts —61— and is provided with a pair of pinions —64— meshing with the gears on one of the shafts —61—, said additional shaft being provided at one end with a hand crank —65— secured thereto and having its free end provided with a handle —66— and a catch —67—, which latter is normally engaged with one edge of an arm —68—. This arm is journaled at one end upon the shaft —63— in close proximity to the hand crank —65— and has its other end slidable in a hub —69— which in turn is pivoted to a stationary bracket —70— on the under side of an I beam —71— or equivalent stationary over-head support.

A clutch member —72— is secured to one of the gears —62— and is provided with ratchet teeth on one end face for engagement with similar ratchet teeth on the ad-

5 jacent face of a coaxial clutch member —73—, which latter is loose on the adjacent shaft —61— and is attached to one end of a coil spring —74— surrounding said shaft and having its other end bearing upon the opposite shaft —61—, said spring being tensioned to interlock the teeth of the loose clutch member —73— with the opposed clutch member —72— to exert a rotating force upon the adjacent shaft and through the gears —62— to the opposite shaft —61— and thence through the pinions —64— to the hand crank —65— tending to hold the catch —67— in engagement 10 with the arm —68— at a point between the shaft —63— and journal bearing of the hub —69— as shown in Fig. 2.

20 It will be seen upon reference to the drawings that the die supporting part of 25 the carriage including the posts —19—, cross-plate —57— and gears carried thereby are movable about the axis of the shaft —20— through an arc between said shaft and the relatively stationary bearing of the hub —69— and that when the carriage is closed, the catch —67— is normally engaged with the upper edge of the arm —68— so that when the carriage is open by the operation of the piston —42— and its connections with the carriage —18—, the end of 30 the arm —68— carried by the shaft —63— will be rocked downwardly and outwardly and by reason of its engagement with the catch —67— will cause a corresponding turning movement of the hand crank —65— and shaft —63— to impart similar rotary motion to the gears —62— through the medium of the pinions —64—, thereby rocking the crank arms —60— in opposite directions to 35 open the movable die-supporting-plate through the medium of the links —69— as shown by dotted lines in Fig. 2.

40 It is sometimes necessary to close the movable die against the stationary die when the carriage is in its extreme open position to retain in place an extra loose die member during the closing operation of the carriage and in order that this may be conveniently accomplished, the hand crank —65— is made 45 sufficiently resilient to permit its free end to be withdrawn laterally a sufficient distance to disengage the catch —67— from the arm —68—, whereupon said hand crank may be 50 rocked in the proper direction for rotating the pinions —64— and gears —62— assisted by the unwinding tension of the coil spring —74— to close the movable die against the fixed die through the medium of the toggles —56— while the carriage still remains in 55 its full open position, as shown by dotted lines in Fig. 2 at which time the piston —42— will be at the extreme right hand end of the cylinder —41— Fig. 5; the guide-rod —32— will be in a substantially vertical position below the shaft —20— with the slid-

6 ing hub —37— on the lever —34— at the lower end of the guide-rod —32— and opposed to the pivot —35— to lock the carriage in its open position, while the coil springs —24— will be placed under relatively high 70 compression.

75 Then by adjusting the valve controlling lever —51— to the proper position, compressed air will be admitted to the right hand end of the cylinder —41— Fig. 5 to 80 force the piston —42— to the left, thereby rocking the lever —34— and causing the hub —37— on the lever arm —36— to slide upwardly toward the piston —20— about the axis of the pivot —35— until it passes a direct line between the pivots —20— and —35— after which it will slide along the 85 guide —32— away from the pivot —20— until the arm —36— assumes a substantially 90 vertical position, as shown by full lines in Figs. 2 and 5, thereby causing said guide —32— and carriage —18— to assume a substantially horizontal position with the relatively fixed die plate in contact with the nozzle —17— in which position, the carriage 95 will be locked by the substantially vertical position of the lever arm —36— directly over the pivot —35—.

100 During this closing movement of the carriage, the pivotal connection 22 between said carriage and the tubular member —23— is moved through an arc about the axis of the pivot —20— from a position some distance below to a position some distance above a direct line between the pivots —20— and —26—, thereby allowing the springs —24— to expand and to exert their expansive force 105 in assisting the closing operation of the carriage, while at the same time, the arm —68— which was previously in a substantially vertical position will be caused to slide through the hub —69— and to rock about the axis of the pivot of said hub which in turn will cause the pivotal connection —63— between the arm —68— and cross-plate —57— to 110 swing from a position some distance to one side of a direct line between the pivots —20— and —69— to a position some distance to the opposite side of said direct line.

115 The ratio of the gears —62— and —64— is such as to cause the opening and closing movement of the movable die by approximately a quarter revolution of the gear —62— and substantially a half revolution 120 of the hand crank —65—, and when the carriage is being moved from its extreme open position to its extreme closed position with the movable die substantially closed by the operation of the hand crank —65— in the manner previously described, the latter will of course, remain in that position during the closing operation of the carriage with the catch —67— in the path of movement of a cam face —67— on the arm —68— so that 125 as the carriage continues to close, the catch

—67— will ride across the cam face —67'— and assume a position at the opposite side of the arm —68—, as shown by full lines in Fig. 2 ready for the opening movement of 5 the carriage, the toggle levers —56— being adjusted to straighten when the carriage is closed to lock the movable die in its closed position against the fixed die.

The tension of the coil spring —74— may 10 be increased at any time by the application of a spanner-wrench to the clutch section —73—.

What I claim is:

1. In a casting machine of the character 15 described, the combination with a delivery nozzle for the molten metal, a die supporting carriage pivoted to swing to and from said nozzle and means including a spring adapted to be placed under tension during the 20 closing movement of the carriage to exert its power in assisting the opening movement of the carriage.

2. In a casting machine of the character 25 described, the combination of a delivery nozzle for molten metal, a die supporting carriage pivoted to swing to and from said nozzle and means including a spring placed under tension when the carriage is moved to its open position for exerting its power to 30 assist in closing the carriage.

3. In a die casting machine of the character 35 described, the combination of a delivery nozzle for the molten metal, a carriage movable into and out of registration with said nozzle, a sectional die mounted on the carriage and movable therewith into and out of operative connection with said nozzle, means for operating the carriage, additional 40 means for moving one of the die sections away from the other as the carriage is open, and including means whereby the relatively movable die section may be closed at will upon its companion section.

4. In a casting machine of the character 45 described, the combination of a delivery nozzle for molten material, a die-supporting-carriage pivoted to swing to and from said nozzle, means for operating said carriage, a stationary bearing and resilient toggle-connections between said bearing and carriage.

5. In a casting machine of the character 55 described, the combination of a delivery nozzle for molten material, a die-supporting-carriage pivoted to swing to and from said nozzle, means for operating said carriage, a stationary bearing and resilient toggle-connections between said bearing and carriage having a flexing joint movable across 60 and beyond a direct line between the carriage-pivot and said bearing.

6. In a casting machine of the character 65 described, the combination of a delivery nozzle for molten metal, a pivoted die-carriage movable toward and from said nozzle, a sec-

tional die mounted on said carriage, means for operating said carriage, a die-supporting-plate mounted on the carriage and movable toward and from the axis of movement thereof, a relatively stationary bearing, and 70 connections between said stationary bearing and carriage for moving said plate in reverse directions as the carriage is open and closed.

7. A casting machine comprising in combination a pressure chamber, a nozzle, a sectional die, a pivoted die carriage in which said sectional die is mounted, having at one end a guideway slidably engaged by a crank member mounted on a rigid bearing, 80 means for reciprocating said crank member on said bearing whereby said crank member is moved back and forth along said guideway, causing said die carriage to swing in and out of engagement with said nozzle and holding the same in rigid engagement with said nozzle during the casting operation.

8. A casting machine comprising in combination a pressure chamber, a nozzle, a die, a pivoted die carriage in which said die is mounted, having at one end a guideway engaged by a pivoted crank, which when reciprocated causes the die carriage to swing from the casting position in engagement with said nozzle to a position out of engagement with said nozzle, said crank also acting as a means of locking the die carriage into engagement with said nozzle.

9. A casting machine comprising in combination a pressure chamber, a nozzle, a sectional die, a pivoted die carriage having a stationary die plate to which is attached one part of said die and a movable die plate to which is attached another part of said die, means for moving said movable 105 die plate and a stationary bearing co-operative therewith, so that when said die carriage is swung to and from the nozzle the movable die plate is moved to and from the stationary die plate.

10. A casting machine comprising in combination a pressure chamber, a nozzle, a sectional die, a pivoted die carriage having a stationary die plate to which a part of said die is attached and a movable die plate 110 to which is attached another part of said die, means for moving said movable die plate, a stationary bearing co-operative with said movable die plate so that when said die carriage is swung to and from the nozzle, the movable die plate is moved to and from the stationary die plate, means for storing power co-operative with said swinging die carriage and movable die plate 115 whereby power is stored when said movable die plate moves from said stationary die plate and released when said movable die plate moves to said stationary die plate and means for operatively releasing said power to move said movable die plate in 120 125 130

dependent of the movement of said die carriage on its pivot.

11. A casting machine comprising in combination a pressure chamber, a nozzle, a sectional die, a pivoting die carriage having a stationary die plate on which is mounted one part of said die and a movable die plate on which is mounted another part of said die, a guideway rigidly attached to the die carriage, a crank (or member) slidably engaging said guideway and mounted on a stationary bearing, so that when said crank is reciprocated on said bearing it moves along said guideway causing said die carriage to swing in and out of engagement with said nozzle, means for moving said movable die plate on said die carriage, a stationary bearing pivotally mounted cooperative with said means for moving said

movable die plate so that when said die carriage is swung in and out of engagement with the nozzle, said movable die plate is moved to and from said stationary die plate.

12. In a casting machine, a fire box, a melting pot, a pressure conduit below said melting pot terminating in a nozzle above said melting pot, the other end of said conduit being larger in diameter than said nozzle and being jacketed so as to receive the heat from the fire box and being connected with means to supply fluid pressure to the contents of said pressure conduit.

In witness whereof I have hereunto set my hand this 24th day of June, 1921.

EDGAR N. DOLLIN.
